Primary Examiner—Mimosa De
(74) Attorney, Agent, or Firm—Workman Nydegger(57) **CLAIM**

The ornamental design for a furniture base, as shown and described.

DESCRIPTION

FIG. 1 is a perspective view of a furniture base showing our new design;

FIG. 2 is a top plan view thereof;

FIG. 3 is a bottom plan view thereof;

FIG. 4 is a first side view thereof;

FIG. 5 is a second side view thereof; and,

FIG. 6 is a third side view thereof.

The broken lines are for illustrative purposes only and form no part of the claimed design.
